CLAIM

The ornamental design for a pool caddy assembly, as shown and described.

DESCRIPTION

FIG. 1 is a perspective top front right view of a pool caddy assembly, including a caddy feature, a first bracket feature, and a second bracket feature, showing our new design;

FIG. 2 is a perspective top rear left view thereof;

FIG. 3 is a front elevation view thereof;

FIG. 4 is a rear elevation view thereof;

FIG. 5 is a right elevation view thereof;

FIG. 6 is a top plan view thereof; and,

FIG. 7 is a bottom plan view thereof.

The broken lines form no part of the claimed design and depict portions of the pool caddy assembly that form no part of the claimed design.
